UNITED STATES PATENT OFFICE.

MILTON C. KENNERLY, OF STUART, OKLAHOMA.

CHURN-SUPPORT.

1,337,362.

Specification of Letters Patent. Patented Apr. 20, 1920.

Application filed January 24, 1920. Serial No. 353,745.

To all whom it may concern:

Be it known that I, MILTON C. KENNERLY, a citizen of the United States, residing at Stuart, in the county of Hughes and State of Oklahoma, have invented certain new and useful Improvements in Churn-Supports, of which the following is a specification, reference being had to the accompanying drawings.

10 This invention relates to an improved support for churns and an object of the invention is to provide a support of this kind which is simple, efficient and practical in construction and is capable of being manufactured for a relatively low cost and sold at a reasonable profit.

There are certain churns manufactured and placed on the market by the Dazey Churn and Manufacturing Company of St. 20 Louis, Missouri, and of such a size as to be supported upon the lap or upon the legs of the operator while in a sitting posture. These churns include a rectangular shaped glass jar or body adapted to hold two, three 25 or four quarts of cream and they are usually operated by supporting them upon the lap or the legs of the operator.

The present invention aims to provide an improved support for churns of this character in order to more efficiently support the 30 churn on the legs of the operator and to render the task of churning, which usually requires from thirty to forty minutes, less tiresome.

35 To these ends it is the aim to provide a support comprising a rectangular body or receptacle for the reception of the lower end of the churn body, in combination with means projecting from opposite sides of the 40 receptacle to engage upon the legs of the operator to hold the receptacle firm and rigid, while operating the churn.

The invention further aims to provide certain of said means which project from 45 opposite sides of the receptacle, with extensions, against which the sides of the legs, particularly adjacent the knees, may bear, in order to insure holding the receptacle firm.

50 A still further object of the invention is to provide certain of the supporting means

of opposite sides of the receptacle with adjustable elements, whereby the legs of the operator may be positioned close together or considerably spread apart, as the operator may require, in order to insure holding the receptacle in its proper position.

The invention further aims to construct the receptacle so that a slight pressure will be necessary to cause the churn body to enter 55 the receptacle and be supported firmly by friction with relation to the receptacle.

While the design and construction at present illustrated and set forth is deemed preferable, it is obvious that as a result of 60 a reduction of the invention to a more practical form for commercial purposes, the invention may be susceptible to changes, and the right to these changes is claimed, provided they are comprehended within the 65 scope of what is claimed.

The invention comprises further features and combination of parts, as will be herein-after set forth, shown in the drawings and claimed.

75 In the drawings:—

Figure 1 is a plan view of the improved support constructed in accordance with the invention,

Fig. 2 is a sectional view on line 2—2 of 80 Fig. 1, and

Fig. 3 is a sectional view on line 3—3 of Fig. 1, and also showing the churn mounted 85 in the receptacle and illustrated in section.

Referring more especially to the drawings, 1 designates a receptacle which may be any suitable size and any depth, and constructed of any suitable metal, preferably sheet metal of any kind. The bottom of the receptacle adjacent the marginal flange 90 thereof has secured thereto as at 2, cleats 3. These cleats are designed to be engaged by the bottom or lower end of the churn body 4 so as to hold the churn body spaced upwardly from the bottom of the receptacle. 95 As previously stated, the receptacle is designed to be made of such a size as to require a slight pressure in order to cause the churn body to enter the receptacle with sufficient friction to hold the churn body in 100 firm relation to the support.

While it is true that any form of con-

struction of churn may be supported upon the legs of the operator, the present churn comprises a rectangular shaped glass jar or body 5 provided with an upper reduced 5 threaded extension 6 to which a cover 7 is threaded. A bracket 8 is mounted upon the upper face of the cover and in bearings thereof a crank shaft 9 is mounted. A beveled gear 10 is carried by and movable with 10 the crank shaft 9 and it meshes with a beveled pinion 11, which is carried by the upper end of the churn dasher shaft 12. The shaft 12 is provided with churning elements 13, and its lower end engages a thrust bearing 14, while its upper end engages bearings 15 of the cover 7 of the bracket 8. It will be noted that by imparting movements to the crank shaft motion may be imparted to the shaft 12 through the medium of the 15 beveled gears 10 and 11.

In order to facilitate the churning operation and to render it less tiresome and tedious, the receptacle has riveted to the under part and certain opposite sides thereof 25 at the front and rear of the receptacle metallic straps 16 and 17. These straps are secured by rivets or the like 18 to the receptacle. The straps 16 and 17 have substantially their central portions made U-shaped, 30 as shown, to conform to the contour of the receptacle. The extended parts of the strap 17 constitute supporting arms 19, which are designed to engage the legs of the operator near the body thereof, to assist in holding 35 the receptacle firm and in its proper position on the legs of the operator. The strap 16 beyond its rectangular shape (which conforms to the shape of the receptacle) is provided with lateral arms 20. Engaging 40 upon the upper faces of these arms 20 are plates 21, which are provided with elongated slots 22. Screws 23 engage through the slots 22 of the plates 21 and are threaded into the arms 20, and the extremities of 45 their threaded portions are swaged or slightly headed as at 24 to prevent the removal of the screws. Threaded screws 25 extend upwardly through the arms 20 and through the slots 22 of the plates 21, and have threaded on their ends thumb nuts 26. The outer end portions of the plates 21 are curved downwardly as indicated at 27 to 50 conform to and engage the side portions of the legs adjacent the knees of the legs of the operator, in order to firmly hold the receptacle in position.

In using the support for the churn, it is arranged on the legs of the operator so that the arms 19 will rest on the legs at points 55 close to the body of the operator, while the arms 20 will rest upon the legs of the operator near the knees, while the curved parts 27 will engage the sides of the legs adjacent the knees. The operator then adjusts 60 the plates 21 according to the distance it is

desired to spread the legs so that the outer sides of the legs will bear against the curved portions 27 firm enough, to hold the receptacle rigid. Before applying the support to the legs in this manner, the churn body is 70 first forced or wedged frictionally in place in the receptacle. After the support has been so disposed, the operator may very readily operate the handle of the churn without any inconvenience of the churn 75 moving during the rotary movements of the crank shaft and the churning element. When the churning operations are completed the support and the churn may be easily removed, after which the churn body 80 may be detached from the receptacle of the support.

The invention having been set forth, what is claimed as new and useful is:—

1. In a support for a churn, the combination with a receptacle conforming to and adapted to receive the churn body, said receptacle having oppositely arranged laterally extending arms, certain of the arms engaging the legs of the operator adjacent 90 the body of the operator, certain other of said arms resting upon the legs adjacent the knees, and means carried by the last mentioned arms to engage the sides of the legs of the operator adjacent the knees when the 95 legs are spread apart so as to hold the receptacle and the churn body in an upright rigid position.

2. In a support for a churn, the combination with a receptacle conforming to and 100 adapted to receive the churn body, said receptacle having oppositely arranged laterally extending arms, certain of the arms engaging the legs of the operator adjacent the body of the operator, certain other of 105 said arms resting upon the legs adjacent the knees, and means adjustably carried by the last mentioned arms to engage the sides of the legs of the operator adjacent the knees when the legs are spread apart 110 so as to hold the receptacle and the churn body in an upright rigid position.

3. In a support for a churn, the combination with a receptacle conforming to and adapted to receive the churn body, said receptacle having oppositely arranged laterally extending arms, certain of the arms engaging the legs of the operator adjacent the body of the operator, certain other of said arms resting upon the legs adjacent the 115 knees, and means carried by the last mentioned arms to engage the sides of the legs of the operator adjacent the knees when the legs are spread apart so as to hold the receptacle and the churn body in an upright rigid position, and plates having elongated 120 slots engaging upon the last mentioned arms, means carried by the last mentioned arms and engaging through the slots of said plates for guiding the same when adjusted, 125 130

means passing through the last mentioned arms and also through the slots and provided with devices for holding the plates in different adjusted positions, according to the spread of the legs of the operator, said plates having outer curved portions adapted to engage the sides of the legs of the opera-

tor adjacent the knees, whereby the pressure of the legs when spread apart will hold the receptacle in position firmly. 10

In testimony whereof I hereunto affix my signature.

MILTON C. KENNERLY.
